Primary Examiner—Louis S. Zarfas*Assistant Examiner*—Robert A. Delehanty*Attorney, Agent, or Firm*—Stinson, Mag & Fizzell, PC[57] **CLAIM**

The ornamental design for a baseball glove, as shown and described.

DESCRIPTION

FIG. 1 is a rear perspective view of a baseball glove showing my new design.

FIG. 2 is a left side view thereof.

FIG. 3 is a right side view thereof; and,
 FIG. 4 is a top elevational view thereof.

The broken line showing of a baseball glove is for illustrative purposes only and forms no part of the claimed design.
